CLAIM

The ornamental design for a container for oil collection and storage, as shown and described.

DESCRIPTION

FIG. 1 is a top plan view of a container for oil collection and storage showing my new design;

FIG. 2 is a top plan view thereof, a portion of the top shown broken away;

FIG. 3 is a cross-sectional view thereof, taken on line 3—3 of FIG. 2;

FIG. 4 is a cross-sectional view thereof, taken on line 4—4 of FIG. 2;

FIG. 5 is a right side elevational view thereof;

FIG. 6 is a left side elevational view thereof;

FIG. 7 is a top plan view thereof, the cover is removed for clarity of illustration;

FIG. 8 is a bottom plan view thereof;

FIG. 9 is a front elevational view thereof;

FIG. 10 is a rear elevational view thereof; and,

FIG. 11 is a top perspective view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. II.
